VALVE OR DRAIN PLUG

James Howard Williams, Providence, R. I., assignor to General Fire Extinguisher Company, Providence, R. I., a corporation of Delaware

Application October 28, 1933, Serial No. 695,618

1 Claim. (Cl. 251—56)

This invention relates to an improved valve or drain plug. More especially it has to do with a device adapted to be connected to the ordinary drain hole of a container for liquids such as oil, water, molasses, and the like.

The object of the invention is to provide a simple, rugged device which can readily be inserted in such a drain hole (or in a suitable adapter previously inserted in the hole) and act normally to retain the liquid in the container like the customary plug. A further object is the provision of a simple valve in the device which can easily be opened or closed by a person standing nearby.

The preferred form in which I have contemplated applying the principles of my invention is shown in the accompanying drawing, but this is to be taken as merely illustrative because it is intended that the patent shall cover by suitable expression in the appended claim whatever features of patentable novelty exist in the invention disclosed.

In the drawing:

Figure 1 is a plan view of the device when closed;

Figure 2 is a similar view with the device open;

Figure 3 is a vertical section taken as on line 3—3 of Figure 1;

Figure 4 is a vertical section taken as on line 4—4 of Figure 2;

Figure 5 is a bottom plan view of the device closed;

Figure 6 is a like view of the device open;

Figure 7 is a front elevation of the device showing how a removable hand rod may engage it; and

Figure 8 is a vertical section as on line 8—8 of Figure 4.

Referring more particularly to the drawing, the device has an externally threaded hollow stem 10 adapted to be screwed into the drain hole of a container. This stem can be made in various sizes or, if a limited number of sizes are preferred for purpose of standardized manufacture, an adapter (not shown) can readily be provided 45 to fit into the drain hole and in turn receive the stem of the device.

Associated with the stem is a plate member 12 having on opposite sides depending side flanges 14 (see Figure 8) with a turned-in lip 16 along 50 the bottom edges thereof to form opposed guideways 18. The latter receive the edges 20 of another plate member 22, hereinafter called the slide, which has a depending socket 24 with an inturned flange 26 at the bottom. Resting on 55 this flange is a coiled spring 28 which presses up-

ward against an out-turned flange 30 on a cup-shaped member 32 designated the cage. A ball 34 nests in this cage so that a portion of its spherical surface is above the top edge of the cage.

In assembling the device the spring is dropped into the socket of the slide, the cage is inserted within the spring with its flange engaging the top coil thereof, and the ball is placed in the hollow of the cage. The edges 20 of the slide are 10 then pushed into the guideways 18 of the stem plate. When the upstanding surface of the ball reaches the plate 12 it slides thereunder and in so doing depresses the cage as the spring yields. The base of the cage projects through a hole 26a 15 in the bottom of the slide as seen in Figures 4 and 8. As the latter continues to move along the guideways the ball rolls or slides on the under-surface of plate 12 until the lower end of a drain hole 36 through the stem and plate is reached. 20 There the ball is snapped into the hole by the force of spring 28 and comes to rest on the edge of the hole making a tight seat therewith. Preferably the bottom edge of the hole is slightly beveled as 36a, best shown in Figures 4 and 8. 25 The device is now closed against drainage through the hole, the parts being in the positions shown in Figures 1, 3, 5 and 7.

When it is desired to open the device, the slide is pulled or pushed in the reverse direction. This 30 may be done by grasping the depending socket 24 in the hand or a rod 38 may be used. As shown in Figure 7, such a rod may have a looped end 40 large enough to slip by one or more lugs 42 provided on the bottom edge of the socket. These 35 aid in holding the looped end on the barrel of the socket while the slide is being moved. Of course, a permanently attached rod could be employed if desired.

As the slide begins to move, the ball is depressed, the spring 30 yielding and the cage again projecting through the hole 26a. The slide continues to move until the drain hole is fully exposed as best seen in Figure 6. To prevent the 40 slide from being entirely separated from the stem plate, extended side arms 44 are provided with a cotter pin 46 so disposed that its ends engage the ends of the guideways on the body. 45

After the container has been drained sufficient- 50 ly, the hook is again applied to the socket and the slide is moved in the opposite direction to permit the ball to snap back into its seat around the edge of the drain hole. To avoid any undue movement in this direction the slide is provided 55

with ears 48 which engage the guides' ends in like manner as does the removable cotter pin.

The device is simple to manufacture, being made largely of castings, is easy to install and is 5 readily opened or closed. When opened, the valve parts are entirely clear of the orifice and the liquid can fall straight through possibly necking in a little at the bottom of the hole and thus hardly touching the valve seat. Since the 10 latter is depending, no dirt or other foreign matter will come to rest thereon. And when the slide is moved to closed position, the ball automatically finds its seat, being self-centering.

I claim:

15 A device of the character described comprising a stem adapted to be connected with a drain hole of a container and having a passageway therethrough; a plate member associated with said stem having parallel depending guideways along 20 opposite edges; a slide member movable along said guideways transversely to the axis of said

passageway, having a depending socket with an inturned flange and outturned lugs at the bottom; a cup member arranged in said socket and having an outturned flange at its upper end; a spring coiled around said cup member and engaging the said flanges and tending to move the cup member toward the plate member; and a ball seated in said cup member and arranged to be seated on the edge of the passageway to close the same; the said spring yielding to permit the ball 10 to be withdrawn from the passageway and move along said plate member as the slide member moves along said guideways; and means for moving said slide member comprising a rod having a hooked end adapted to slip by said outturned 15 lugs and engage the depending socket of the slide; the said lugs preventing downward dislodgment of the rod from the slide during the moving thereof.

JAMES HOWARD WILLIAMS. 20
